(No Model.)

J. STEELE.

CHISEL CUTTER FOR SASH AND BLINDS.

No. 368,556.

Patented Aug. 16, 1887.

ATTEST,

*John H. Redstone
J. H. Redstone*

INVENTOR,

Joseph Steele

UNITED STATES PATENT OFFICE.

JOSEPH STEELE, OF SAN FRANCISCO, CALIFORNIA, ASSIGNOR OF ONE-THIRD
TO ALBERT ALBRECHT, OF SAME PLACE.

CHISEL-CUTTER FOR SASH AND BLINDS.

SPECIFICATION forming part of Letters Patent No. 368,556, dated August 16, 1887.

Application filed October 12, 1886. Serial No. 215,988. (No model.)

To all whom it may concern:

Be it known that I, JOSEPH STEELE, a citizen of the United States, residing in the city and county of San Francisco, and State of California, have invented a new and useful Chisel-Cutter for Sash and Blinds, of which the following is a specification.

My invention relates to chisel-cutters for setting shutter and door hinges, and has for its object the production of a device of this character which shall be simple in its construction and effective in its operation.

The invention consists in certain features of construction and combinations of parts, hereinafter fully described, and pointed out in the claims.

In the drawings, Figure 1 is a perspective view of a chisel-cutter embodying my invention. Fig. 2 is a side elevation of the same. Fig. 3 is a plan view. Fig. 4 is a longitudinal vertical section, and Fig. 5 is an end elevation.

Referring to the drawings, A represents the body of the chisel, and A' a shank or handle preferably formed integral therewith. The body of the chisel has a tapering top drawn out at its front end to form a cutting-edge, a. Depending from the top of the chisel are sides b, bent inwardly and downwardly, as at b'.

B represents a gage, which consists of a strip

or plate having downwardly-extending ends c. The plate of the gage is adapted to fit in a recess, I, on the upper face of the chisel, so as to be flush with the latter, and the ends c fit in grooves I' in the sides of the chisel and are 35 adjustably held by means of screws G, which pass through slots C in said arms.

D represents a gage-frame, which consists of parallel side bars, D', connected by an end bar, d. Extending upwardly from the bars D' are 40 slotted arms E, which fit in the grooves H in the sides of the chisel, and which are adjustably held in said grooves by screws F, so that the gage-frame D may be raised and lowered as desired. 45

I claim—

1. The combination, with the chisel A, having the side and top grooves, of the gage B, adapted to fit in said grooves and adjustable to or from said top groove, substantially as described. 50

2. The combination, with the chisel A, having the side grooves, of the gage-frame D, the slotted arms E, fitting in said grooves, and set-screws, substantially as described.

JOSEPH STEELE.
